APPARATUS FOR TEEMING INGOT-MOLDS.

1,298,034.

Specification of Letters Patent. Patented Mar. 25, 1919.

Application filed December 6, 1918. Serial No. 265,582.

To all whom it may concern:

Be it known that I, EMIL GATHMANN, a citizen of the United States, residing in Baltimore, State of Maryland, have invented 5 certain new and useful Improvements in Apparatus for Teeming Ingot-Molds, of which the following is a specification.

This invention relates to the casting of metal ingots or the like and particularly 10 to the pouring or teeming of metallic ingot molds.

Heretofore the common practice has been to teem a series of molds from a ladle of large size containing sufficient molten metal 15 to fill a plurality of molds one after the other and some attempts have been made to fill two or more molds simultaneously from the same ladle, but this latter method has not been successful inasmuch as often one 20 mold was filled before the other or others owing to irregularities in the flow of metal through the passages leading from the ladle; therefore, the common practice is to fill the molds separately, the metal passing from the 25 ladle through a valve-controlled nozzle in a large stream and with high velocity under the great hydraulic pressure of the large quantity of molten metal in the ladle. This stream of metal at first strikes the bottom 30 of the mold chamber and often injures it and furthermore during the entire period of teeming the metal splashes violently causing it to mingle with air and to strike with great force against the side walls of the mold 35 chamber in such manner as to cut the mold walls and to cause the molten metal to weld to said walls and thus not only impede the proper shrinking of the ingot away from said walls and also the easy stripping of the 40 ingot from the mold, but it often results in producing what are called "cold shuts" or "scabs" on the ingot which are serious defects that cannot be remedied by subsequent processes and often result in imperfect 45 products from the ingots.

It is also well known that during the teeming of a mold the molten metal as it falls into the mold chamber is deflected and driven with considerable force against the 50 side walls of the mold and a skin is formed on these walls above the level of the more quiet metal in the mold. This skin is somewhat mushy or soft and often during the

pouring of the metal parts of it are cut or broken away in an irregular manner, leaving 55 defects in the finished ingot. The difficulties above mentioned have long been recognized and attempts have been made to overcome them in various ways as by providing means for subdividing the stream of 60 metal delivered by the ladle in such manner that the speed or momentum of the metal as it enters the mold chamber will be reduced, the object being to reduce or prevent the formation of "cold shuts" or "scabs" and 65 to otherwise remedy the difficulties above mentioned. Mold teeming devices of this class have, however, in all cases been in the form of portable containers which were interposed between the ladle proper and the 70 top of the mold, the metal flowing freely from the nozzle of the ladle into the container which was provided with a plurality of openings through which the metal was delivered to the mold. In such cases the 75 hydraulic pressure of the metal in the ladle was only used to force the metal through the outlet of the ladle, none of such pressure being utilized for forcing metal in a subdivided condition or with reduced velocity 80 into the mold, therefore the speed of delivery was unduly reduced and furthermore the metal was unduly cooled owing to the fact that it passed through an open air space 85 between the nozzle and the perforated receptacle thereunder. In such cases also it was not possible to pass the molten metal uniformly through all the openings or perforations in the receptacle and it was not possible to regulate the flow of the metal 90 through said openings. Furthermore, owing to this irregularity in the flow of metal through the perforated receptacle the metal often became thickened or mushy and some or all of the openings would be closed, therefore this method of pouring molds has never, 95 so far as I am aware, been used, certainly its use has not been general.

According to my invention, I reduce the velocity without materially reducing the volume of metal discharged from the ladle into the mold and I utilize the hydraulic pressure of the mass of molten metal in the ladle to force the metal not only with sufficient velocity and with the required volume from the 100 ladle but also to force it with reduced veloc- 105

ity and substantially the same volume into the mold chamber. In this way a much quieter pouring of the mold is effected without any loss of time. Preferably the solid stream of molten metal passing from the ladle through the valve-controlled orifice is made to impinge upon a baffling device arranged in a chamber which distributes or directs the molten metal with its high velocity thus modified to a series of discharge openings through which the metal passes in a plurality of relatively small streams each of which individually is of smaller cross section than that of the outlet opening of the ladle but which are collectively of greater cross section than said outlet opening. In this way the velocity or speed of the molten metal coming from the ladle is greatly reduced and yet the volume of metal passing from the ladle is not materially changed. Therefore the ladle can be emptied at the same speed as before but with the additional advantages above specified. Furthermore, the metal passing through the delivery openings is constantly under hydraulic pressure which insures the constant and unimpeded delivery of the metal, which has no chance to cool or solidify in such manner as to delay the operation.

30 In carrying out my invention, I preferably employ a ladle or container of sufficient capacity to fill in succession a plurality of molds and in the bottom of the ladle I provide an outlet opening controlled by a valve or stopper which may be of usual construction. The metal passes through the outlet opening in a relatively large stream but instead of passing directly into the mold as heretofore it enters what I call a distribution chamber of larger capacity than the outlet of the ladle and containing a baffling device which receives the stream of molten metal, changes its velocity and deflects the metal or distributes it to a series of discharge openings through which the metal passes to the mold with reduced velocity but under hydraulic pressure and yet in such manner as to teem the mold in the required time without danger of the metal cooling or solidifying in the ladle before it is emptied. The metal is so delivered through the discharge openings that it enters the mold chamber in a much quieter manner than heretofore causing less boiling or splashing and preventing the cutting or breaking of the mold walls or the skin forming on the sides thereof and also preventing the welding of metal to the mold walls which was a serious defect in methods heretofore employed. Other features of my invention will be hereinafter more fully described.

In the accompanying drawings:—

Figure 1 is a sectional view of a metallic ingot mold and a ladle for teeming the mold

constructed in accordance with my invention.

Fig. 2 shows a section on the line 2—2 of Fig. 1.

Fig. 3 shows a section on the line 3—3 of Fig. 1.

Fig. 4 is a detail view in perspective intended to illustrate particularly the construction of that part of the nozzle in which the velocity of the stream of metal passing from the ladle is reduced and the metal is deflected and distributed to the discharge openings of the nozzle. 75

Referring to Fig. 1, I have shown a well known form of mold A, resting on a stool or base A'. It will be observed that the walls of the mold A are thinner in their upper portions than in their lower portions so that the formation of "pipe" in the ingot is reduced or eliminated in a manner now 80 well known, but it will be understood that my invention may be applied to molds of other construction.

The ladle B is in general of well known construction except that the devices applied to the outlet of the ladle are made in accordance with my invention. As usual, the ladle comprises an outer casing or shell b of metal and a lining b' of refractory material, such as fire brick, and the ladle is provided with ears b² which may be engaged by suitable devices b³ for supporting the ladle and these devices may be connected with cranes or other mechanism for moving the ladle from place to place as desired. An opening x is formed in the bottom of the ladle and is preferably centrally located as indicated, and this opening is controlled by a valve or stopper B' of well known construction which may be provided with any suitable devices for operating it. The devices applied to the outlet opening x constitute generally what may be termed a nozzle. In Fig. 1 this nozzle comprises a metallic casing D which may be detachably connected with the bottom of the ladle by bolts or other suitable devices d. This casing incloses and supports a block E of refractory material, chambered and provided with passages for the molten metal. The part d' projects into the opening x and is suitably formed to provide a valve seat e for the valve or stopper B'. Below the valve seat there is a passage f of relatively large cross section through which the molten metal passes from the ladle and this may be termed the outlet of the ladle. Said passage f delivers to a chamber G, the preferred form of which is clearly indicated in Fig. 4 of the drawings and is also indicated in other figures. This chamber I call the distribution chamber inasmuch as it divides the stream of metal flowing through the passage f and directs the metal to a plurality of delivery openings g each of which is of smaller cross section than the outlet pas- 95

100 105 110 115 120 125 130

sage f . Preferably these passages g are arranged in an annular series and while each one is of less cross sectional area than the passage f , collectively their cross sectional area is much greater; preferably about 50% or more greater. Within the distribution chamber is located a baffling device H which assists in distributing or directing the metal to the discharge openings g and which also receives the full force or impact of the stream of metal passing from the ladle and serves to reduce its velocity while at the same time deflecting the metal in the manner before specified.

15 While the velocity of the metal passing through the outlet openings g is greatly reduced it is forced through the outlet openings by the great hydraulic force or pressure of the mass of metal in the ladle, this pressure being sufficient at all times to deliver the metal with such speed as to prevent the cooling or the solidifying thereof before it is discharged into the mold chamber. As before stated I preferably divide the stream 20 of metal passing from the ladle into a plurality of relatively small streams arranged in an annular series but it is not necessary that said openings should be so arranged, and the number of such openings is not 25 essential so far as some features of my invention are concerned, it being important in this connection merely to so reduce the velocity of the metal passing from the ladle and before its entry into the mold chamber 30 that it shall not injure the walls of the mold or cut away or injure the skin of the ingot during its process of formation. It is important, however, in this connection, for the reasons before stated, that the metal shall 35 be forced with reduced velocity by the hydraulic pressure of molten metal in the ladle and that the passage of a relatively large solid stream of molten metal from the ladle to the mold should be avoided.

40 The passages for the metal from the ladle to the mold are preferably all formed in a single block E of refractory material, as illustrated in Fig. 1, and the walls of these passages are so disposed as to avoid the 45 formation of shoulders or corners which would unduly impede the flow of the metal through the nozzle. Preferably an annular series of discharge openings is provided but these passages need not necessarily be arranged in an annular series and furthermore they may be merged and a similar result obtained, *i. e.* the single solid stream of metal will be so changed as to reduce the velocity of the metal entering the mold and 55 furthermore the force or impact of the metal will be reduced or distributed, resulting in a much quieter pouring operation without any loss of time in filling the mold.

I preferably so proportion the cross sectional area of the passages or channels in

the nozzle that the combined area of the discharge openings is larger by approximately 50% or more than that part of the nozzle which communicates directly with the ladle. I may therefore use any desired number of 60 discharge openings in the nozzle so long as they are of such size when combined as to reduce the velocity of the metal passing through the nozzle without materially decreasing the volume of metal delivered during any period.

It will be observed by reference to Fig. 1 that the solid stream of metal passing through the passage f is enlarged into a substantially cylindrical or hollow body of 65 metal entering the mold, and while several distinct streams of metal are included in this cylindrical body it is obvious that they may be merged and yet produce a satisfactory result because in either case the velocity 70 of the metal entering the mold is reduced, the impact of metal on the metal in the mold is distributed and the violent disturbances heretofore encountered are avoided. Furthermore, in all cases the direct impact of the metal passing from the ladle is received by the baffling device in the distribution chamber. This serves also to reduce the velocity of the metal and yet it does not 75 impede the volume of metal delivered by 80 the nozzle.

The size or cross sectional area of the intake passage in the nozzle is in present practice, as is well known, usually made as small as will, with the required factor of safety, 85 drain the ladle of its molten liquid burden of metal within the time period necessary to teem or cast a certain number of ingots. For example, a ladle filled with a burden of 90 50 tons of steel should be fitted with a 95 discharge opening of 2 inch diameter for filling each of 25 ingot molds in succession with 2 tons of molten steel; the time of teeming or casting each individual ingot being approximately one minute, the actual 100 pouring period is 25 minutes, the ladle or the molds being moved into teeming or casting position for each ingot made; one-fifth of a minute or collectively 5 minutes being 105 taken for thus filling a group of 25 molds. By experiment it has been found that a ladle with a burden of 50 tons of molten liquid steel will retain the steel in its molten condition if placed in the ladle at a suitable temperature from the melting furnace 110 for a period of from 35 to 45 minutes, a factor of safety as to the time of teeming or casting through a 2 inch nozzle from 5 to 10 minutes is thus obtained. The importance of not unduly increasing the time 115 of teeming or casting the burden of molten steel from a ladle will thus be understood from the example above explained, and it will also be understood that it is impossible 120 or improper to greatly decrease the volume 125 of the nozzle.

or weight of metal teemed from the ladle within a specified time. A nozzle made in accordance with my invention is adapted to be firmly fixed or secured to the ladle while the latter is empty and reasonably cool. A new nozzle is required for every second to sixth heat of the molten metal carried by the ladle, the life of the nozzle depending considerably upon the grade of metal being cast, its temperature and other factors well known to those skilled in the art so that the nozzle as a whole, while adapted to be firmly secured to the ladle, is detachably connected therewith.

15 The ladle equipped with a nozzle made in accordance with my invention is operated in precisely the same way as those usually employed, the stopper B' being made to control the delivery of the metal from the ladle. As 20 the molten metal enters the mold that portion which comes in contact with the relatively cool inclosing mold walls and stool is very rapidly frozen or solidified into a semi-solid or mushy condition forming what is 25 termed the relatively thin skin of the ingot within which the inner body of the ingot later on solidifies or freezes. As the pouring operation continues and the interior of the ingot is formed the skin gradually thickens 30 and becomes more solid and strong.

The vertical walls or initial skin of the ingot grows as the ingot increases in height and although these walls are semi-solid they are extremely tender or in a mushy state 35 due to the intense heat of the still liquid interior mass of the ingot. It is extremely important and well known to those skilled in the art that this skin of the ingot should not be disrupted or broken as such breaks 40 of the mushy skin or semi-solid skin will not properly heal or close and if breaks or cracks are once formed they usually remain as surface defects in otherwise sound, homogeneous ingots or in the finished product.

45 I have found that one of the primary causes of such surface defects in ingots is due to the improper teeming from the ladle to the mold of a solid stream with high velocity which may in a great way be 50 remedied by more quietly and gently delivering the liquid metal into the mold cavity than had heretofore been done.

55 It is known that liquid steel weighs approximately one-quarter pound per cubic inch, and the cross section of a two-inch stream of liquid steel passing from a two-inch nozzle will thus weight $3.14 \times 12 \times .25$ per foot of height or approximately 10 pounds. As the ladle is frequently filled 60 with 10, 12 or more feet depth of steel a pressure in the nozzle from 100 to 125 pounds per stream area at the nozzle is common practice. As iron ingot molds are of considerable height, say from 6 to 8 feet 65 an additional weight of from 60 to 80

pounds is imparted to the descending column of the highly heated liquid steel. The impact of this mass of liquid steel is taken, first by the stool or bottom closure of the mold and second by the body of liquid steel which has already entered the mold and which forms the impacting cushion as the ingot grows or increases in size in the mold cavity due to the incoming liquid metal from the ladle. As the force of impact of any body is, as the square of the velocity, times the weight of the said body the reduction of the velocity of the impacting body is of prime importance in cutting down the energy of the blow. This velocity, due to 75 the height of liquid steel in the ladle and the hydraulic pressure caused thereby, is brought under control by my improvements in which I suitably proportion the discharge area of the nozzle to the area of the outlet 80 passage from the ladle.

85 For example, if the outlet from the ladle has a cross section of two square inches and the delivery openings have a cross section of four square inches and assuming the 90 velocity of stream flowing through the outlet of the ladle as 10 feet per second the same volume or amount in weight of metal will flow through the four square inch delivery openings at a velocity of 5 feet per 95 second, provided of course the direction of the stream from the inlet to the nozzle is first diverted by means of a baffling device or by means of a distribution chamber having a larger cross sectional area. The actual 100 impact value of a 5 foot per second and a 10 foot per second stream is obviously as 5 squared is to 10 squared or as 1 is to 4 for the same volume or weight of the metal stream.

105 Fig. 1 indicates how the mushy skin is formed in the mold and this is incident to all casting operations of the kind to which my invention relates. Where the velocity of the metal entering the mold is reduced in 110 the manner before described, and especially where the solid stream is divided into a plurality of streams, as indicated in the drawings, the breaking down or injury to the skin is avoided or greatly reduced. As indicated in the drawings, where a plurality of streams are employed they are preferably 115 so located as to be grouped around the longitudinal axis of the mold because a direct impact of even a relatively small stream 120 would injure or break through the mushy walls or skins while the ingot is in process of formation. Direct impact or even deflected impact of a single large stream with the walls of the mold cavity either above or 125 below the mushy skin of the ingot during the process of ingot formation is also liable to cause serious defects in the walls of the ingot such as the formation of cold shuts or even actual welding in the ingot surface at 130

various points to the mold walls thus preventing the ingot from freely shrinking during the cooling or solidification thereof and consequently causing tears or cracks in the surface of the skin of the ingot.

It will be observed that the discharge openings or passages *g* are arranged vertically and should be at least approximately vertical in order that the streams of metal 10 entering the mold shall be delivered in a substantially vertical direction. If this were not so the metal would strike against the side walls of the mold and defeat the objects of my invention, for the reasons hereinbefore explained.

In the drawings, I have assumed that the cross sectional area of the passage *f* has a diameter of two inches, while the discharge openings *g* are each one inch in diameter so 20 that the cross sectional area of the resulting discharge opening is double that of the outlet opening *f*, but as before explained this relative arrangement is not essential but it is important that the area of discharge 25 from the nozzle should be greater than the area of the entrance thereto.

My invention involves not only improvements in the apparatus for teeming molds or in the nozzle for directing the molten metal from the ladle to the mold but it also 30 involves a new method of teeming molds and such method is claimed in my application for Patent No. 265,583, filed Dec. 6, 1918.

I claim as my invention:

1. Apparatus for teeming an ingot mold, comprising a ladle or container of molten metal and a valve-controlled nozzle therefor provided with means for discharging molten metal at reduced velocity and with 40 increased area in an approximately vertical direction into a mold without materially reducing the volume of metal delivered thereto.

2. Apparatus for teeming an ingot mold, comprising a ladle or container of molten metal, and a valve-controlled delivery nozzle therefor provided with a passage of relatively large cross sectional area for the flow 50 of metal from the ladle into the nozzle, an expansion chamber into which said passage delivers and an outlet from said chamber through which the metal passes in an approximately vertical direction to the mold which is of materially greater cross sectional 55 area than the inlet passage to the nozzle, whereby the metal is delivered to the mold from the nozzle in substantially the same volume that it entered the nozzle but at 60 greatly reduced velocity.

3. Apparatus for teeming an ingot mold, comprising a ladle or container of molten metal, and a valve-controlled delivery nozzle therefor provided with a passage of 65 relatively large cross sectional area through

which the molten metal passes from the ladle into the nozzle and with a plurality of outlet passages which are arranged approximately vertically and through which molten metal is delivered to the mold, the 70 cross sectional area of each of said passages being materially smaller than that of the inlet passage but the cross sectional area of said passages collectively being materially greater than the cross sectional area 75 of said inlet passage in order that the metal may be delivered to the mold at a materially reduced velocity as compared with the velocity of the metal entering the nozzle.

4. Apparatus for teeming an ingot mold, 80 comprising a ladle or container of molten metal, and a delivery nozzle therefor provided with inlet and discharge passages of different cross sectional areas, and an expansion chamber between the inlet and discharge 85 passages of greater cross sectional area than the inlet passage, said discharge passages being arranged substantially vertically in order that the metal may be delivered to the mold in an approximately 90 vertical direction.

5. Apparatus for teeming an ingot mold, comprising a ladle or container of molten metal and a delivery nozzle therefor provided with an inlet passage of relatively 95 large cross sectional area, a chamber of still greater cross sectional area at the inner end of said inlet passage, a device in said chamber arranged opposite the inlet passage to receive the impact of inflowing metal, 100 and a plurality of discharge passages communicating with said chamber which are arranged approximately vertically and from which the metal passes in an approximately vertical direction into the mold chamber at 105 reduced velocity as compared with the velocity of the metal entering the nozzle.

6. Apparatus for teeming an ingot mold, comprising a ladle or container of molten metal and a delivery nozzle therefor provided with an inlet passage through which metal passes from the ladle to the nozzle, and a plurality of vertically arranged discharge passages connected with said inlet 110 passage, each of which passages is of less cross sectional area than the inlet passage but whose combined cross sectional area is materially greater than said inlet passage and which deliver directly in a substantially 115 vertical direction to the central portion of 120 the mold chamber without coming in contact with the side walls thereof.

7. A nozzle for teeming ladles having an upper portion adapted to enter an opening in the bottom of the ladle, an integral lower 125 portion through which the molten metal is discharged into the mold, and an intermediate portion provided with an expansion chamber.

8. A nozzle for metal-teeming ladles hav- 130

- ing an upper portion adapted to connect with the bottom of the ladle, a lower portion through which the molten metal is discharged into the mold and which is provided with a series of vertically arranged passages, and an intermediate portion provided with an expansion chamber through which molten metal passes from the ladle to the discharge openings of the nozzle.
10. 9. A nozzle for teeming ladles made of refractory material and having an upper portion adapted to connect with the bottom of the ladle, a lower portion through which the molten metal is discharged into the mold and which is provided with a series of vertically arranged passages, and an intermediate portion provided with an expansion chamber through which molten metal passes from the ladle to the discharge openings of the nozzle, in combination with a metallic container for said refractory material adapted to be secured to the ladle and
- which is open at the bottom to permit the passage of metal through it.
10. A nozzle for teeming ladles made of refractory material and having an upper portion adapted to connect with the bottom of the ladle, a lower portion through which the molten metal is discharged into the mold and which is provided with a series of vertically arranged passages, and an intermediate portion provided with an expansion chamber through which molten metal passes from the ladle to the discharge passages of the nozzle, in combination with a metallic container for said refractory material adapted to be secured to the ladle and which is provided in its bottom portion with a series of openings registering with the discharge passages in the nozzle.

In testimony whereof, I have hereunto subscribed my name.

EMIL GATHMANN.
